UNITED STATES PATENT OFFICE.

CHARLES REHLIN, OF ALLEGHENY, PENNSYLVANIA.

DESIGN FOR A BADGE.

SPECIFICATION forming part of Design No. 25,687, dated June 30, 1896.

Application filed April 10, 1896. Serial No. 587,033. Term of patent 3½ years.

To all whom it may concern:

Be it known that I, CHARLES REHLIN, a citizen of the United States, residing at Allegheny, in the county of Allegheny and State 5 of Pennsylvania, have invented and produced a new and original Design for a Badge; and I do hereby declare the following to be a full, clear, and exact description of the invention, such as will enable others skilled in the art to which it appertains to make and use the same.

My invention relates to a new and ornamental design for a badge.

My badge consists, in general terms, of a 15 central pin provided on each of its opposite sides with a wing or leaf in the form of a parallelogram, the faces of which wings are adapted to receive suitable pictures and inscriptions.

20 My invention is illustrated in the accompanying drawings, in which—

Figure 1 is a front view showing the badge open, and Fig. 2 a view showing the obverse face of the badge.

Referring to the drawings, A represents the 25 central pin, which is provided at its top with the parallel wings B C, which are also parallelograms and constitute the badge part. These parts are hinged to the pin A at e.

The part C of the badge on one face is made 30 in the form of a flag having stars in one corner and parallel stripes adjacent thereto. The remaining faces are plain.

The plain faces of the badge are designed to receive, as above stated, portraits and inscriptions, but the essential parts of my design are the central staff-pin and the side parallelograms.

Having thus described my invention, what I claim is—

40 The design for a badge, substantially as shown and described.

In testimony whereof I affix my signature in presence of two witnesses.

CHARLES REHLIN.
